SWITCH-POINT LOCK.

No. 874,686.

Specification of Letters Patent.

Patented Dec. 24, 1907.

Application filed October 2, 1906. Serial No. 337,094.

To all whom it may concern:

Be it known that I, JAMES B. LATIMER, a citizen of the United States, of Chicago, in the county of Cook and State of Illinois, 5 have invented certain new and useful Improvements in Switch-Point Locks; and I do hereby declare that the following is a full, clear, and exact description thereof, reference being had to the accompanying 10 drawings, and to the letters of reference marked thereon, which form a part of this specification.

This invention relates to a novel switch point lock designed to positively lock the 15 switch points either in their open or closed positions independently of the action of the switch actuating mechanism, whereby derangement of the switch actuating mechanism does not impair the efficiency of the 20 lock.

My novel switch point lock is applicable for use at the locations of manually operable switch stands which operate to open a switch or side track to the main track, and 25 vice versa.

The invention consists in the matters hereinafter set forth and more particularly pointed out in the appended claims.

Among the objects of my invention is to 30 provide a locking device which operates independently of the actuating mechanism of the switch stand to positively lock the switch points in both their opening and closing positions and which is readily reusable to permit the switch to be opened and closed.

A further object of the invention is to provide a switch-point locking device, the operative parts of which are adapted to be set 40 in a releasing or lock-set position, and so constructed that movement of the switch points to one position operates automatically on the lock set parts to positively lock the switch in the position towards which it has 45 just been shifted.

As shown in the drawings: Figure 1 is a plan view of a portion of the main and side track showing the usual switch stand equipment and my improved switch point 50 locking device. Fig. 2 is a side elevation of the locking device showing it in position to lock the switch points in normal or closed position. Fig. 3 is a similar view showing parts of the device in the position they assume 55 when the switch points are unlocked pre-

paratory to throwing the switch. Fig. 4 is a view of said parts when in position to lock the switch points open. Fig. 5 is a fragmentary view taken longitudinally of the switch point lock rod, showing the position 60 of the parts when the switch is locked closed. Fig. 6 is a similar view showing the position of the parts for locking the switch open. Fig. 7 is a view partly in side elevation and partly in section of the switch point locking 65 device. Fig. 8 is an end view of the supporting and guiding base for the locking frame of the locking device.

As shown in the drawings, the switch stand A is located in its usual position relatively to the switch points B B and the main track, and is connected in the usual manner, through the medium of the switch rod A¹, with the switch points to throw the same 70 from one position to the other.

I have herein shown one approved embodiment of my invention but it will be understood that the details of the mechanism may be variously constructed without departing 75 from the essential principle of the invention. 80

My novel locking device, which is independent of the switch stand when operating to lock the switch points, comprises, in general terms, a locking device which is, as a whole, mounted stationary on a suitable support or 85 base, as extensions of the ties B¹, a locking rod C that is connected with the switch points in a manner to be moved laterally inwardly and outwardly during the movement 90 or throw of the switch points in either direction, and coöperating locking means on the stationary portion of the device and the outer end of the rod operating in such manner that the said locking rod is positively locked from endwise movement, and the 95 switch points likewise held from movement in either of their two positions, by said co-operating locking devices. Said coöperating locking devices are independent of the switch operating mechanism so that, notwithstanding impairment of the switch stand or any of its parts, the switch points are held or locked positively in either of the positions 100 which they assume.

Referring now more specifically to the 105 illustrated embodiment of the invention, the lock rod C extends at its inner end beneath the track rail and is connected with a lug c that is fixed to the adjacent switch point; the said lug being formed on a bar c² bolted or 110

otherwise fixed to the said switch point. The inner end of the lock rod is provided with an upturned fork, the arms of which extend on either side of said lug and fastened 5 thereto by a pin or bolt c^3 . The locking device coöperating with the outer end of the lock rod comprises, in general terms, a suitable base D mounted on extensions of the ties B¹, or other stationary support, and a 10 sliding locking frame which slides transversely to the axis of the lock rod; said lock frame carrying locking devices that coöperate with the lock rod for the purpose set forth. The base D is provided with upright 15 standards d d¹ through openings d² of which the said locking frame slides longitudinally of the base. Said locking frame may conveniently consist of upper and lower bars e e¹ that are connected at their ends by 20 filler blocks e² e² attached to said bars by means of rivets or the like.

The central standard d¹ of the base is provided with an opening disposed transversely to the guide opening d² through which extends 25 the outer end of the lock rod, the said outer end of the lock rod and opening being herein shown as rectangular. The lock rod C is provided near its outer end with upwardly and downwardly opening, marginal 30 notches which are adapted for engagement by locking detents e³ e⁴ carried by the frame E. The said locking notches c⁴ c⁵ are located a distance apart equal to the movement of 35 the switch points from their closed to their open positions. The detents e³ e⁴ are located in the same vertical plane with each other, the upper one e³ depending from the lower face of the frame bar e, while the lower one rises from the upper face of the lower frame 40 bar e¹. When, therefore, one of the detents is engaged with one of the notches of the lock rod the other detent stands opposite to the solid or unbroken part of the rod, as clearly indicated in Figs. 5 and 6. The detents are 45 located a distance apart slightly greater than the thickness of the lock bar C at the part thereof which engages the guide standard d¹.

As shown in Fig. 5, the upper detent e³ is engaged with the upwardly opening notch c⁴ 50 of the bar, and in this position the switch points are locked closed. The locking frame is moved endwise to release the detent e³ from the upwardly opening locking notch, thereby unlocking the switch points to permit 55 the switch to be opened. Inasmuch, however, as the lock rod is solid or unbroken in the path of the lower detent e⁴ the movement of the locking frame is arrested by the engagement of said lower detent e⁴ with the 60 lock rod, but not until the upper detent is free from the lock rod. During the subsequent opening of the switch the locking rod C is moved endwise, which is permitted by reason of the disengagement of the detent e³ 65 from the notch c⁴. When, however, the

switch has been thrown open, the lower notch c⁵ is brought opposite the detent e⁴ whereupon the locking frame completes its endwise movement or throw to engage said detent e⁴ with the lower notch of the lock rod 70 in the manner shown in Figs. 4 and 6.

It will thus be noted that the switch points are locked positively in either of their positions and that they cannot be thrown to open or close the switch until after the locking device is released.

Any suitable means may be employed for shifting the locking frame in the manner described, so that after the lock has been released it may be operated to lock the switch 80 points in another position.

As a further and separate improvement, I have provided means operating, after the locking frame has been arrested by the lower detent, and occupying what may be called, a 85 lock-set position, to automatically shift said frame to its final position, wherein the lower detent is engaged with the outermost notch and the switch points locked open. The mechanism for effecting this result, in the 90 present instance, is made as follows:

The lower bar e¹ of the locking frame is provided on its lower face with rack teeth e⁵ that are engaged by the teeth of a gear segment F that is located between lugs d³ d³ depending from the base or bar D of the locking device and fixed to a rock shaft F¹ that has bearing in said lugs d³. To the outer end of said rock shaft is fixed a lever F². The said lever F² is free to swing from one limit of 100 its angular movement to the other and is arrested by suitable stops at the limits of its movement. The lever operates through the rock shaft F¹ and gear segment F to slide the locking frame from one limit of its movement 105 to the other.

In Fig. 6 is shown the position of the lever when the switch is locked in its normal or closed position. In order to release the locking device to unlock the switch points, 110 as shown in Fig. 4, the lever is swung upwardly past the perpendicular and the action of gravity continues the movement of the lever and the parts controlled thereby until arrested by contact of the lower detent e⁴ 115 with the solid part of the lock rod. This position of the parts is what may be termed the lock-set position. Thereafter, when the switch points are thrown open by the switch actuating mechanism, the shifting of the 120 switch points acts to move the lock rod endwise until the lower notch c⁵ of the lock rod is brought opposite to the lower detent e⁴. The weight of said lever thereafter acts to further shift the locking frame and engage 125 said lower detent with its coöperating downwardly opening notch of the lock rod, thus locking the switch in its open position. The latter positions of the parts are shown in Fig. 4. Obviously, the return movement 130

of the locking device to release the same and permit the switch to be again locked closed is the reverse of that just described. It will thus be seen that when the switch is to be 5 shifted, the lever F^2 is swung to its lock-set position, and thereafter when the switch points are swung to one limit or the other of their movement, the said lever operates to automatically lock them in the position 10 described.

The recess between the lug d^3 inclosing the gear segment F is closed at its lower side by a casing d^4 which, together with the lugs, is shaped to receive said gear segment.

15 I claim as my invention:—

1. A switch point lock consisting of a locking device independent of the switch actuating mechanism, a longitudinally reciprocating lock-rod fixed at its inner end to the 20 switch points and adapted for locking engagement at its outer end with said locking device and means controlled by the shifting of the switch points to automatically move said locking device from an intermediate or 25 unlocking position to a locking position.

2. A switch point lock consisting of an endwise movable lock-rod attached to and extending laterally from the switch-points, a locking device coöperating with the outer 30 end of the rod for positively locking the switch-points, means for setting the locking device in a lock-set position to release the switch-points, and means controlled by movement of the switch-points for automatically locking the switch in a position 35 towards which said points are shifted.

3. A switch-point lock consisting of an endwise movable lock-rod attached to and extending laterally from the switch-points, a 40 locking device coöperating with the outer end of the lock-rod for positively locking the switch-points, means for setting the locking device in a lock-set position to release the switch points and gravity acting means controlled by movement of the switch-points for 45 automatically locking the switch in a position towards which said points are shifted.

4. A switch-point lock consisting of a locking device for positively locking the switch-points and embracing an operating lever which swings in a plane transverse to the direction of movement of the switch-points, means whereby said lever is arrested in a 50 releasing or lock-set position, and means whereby the lever swings to its locking position upon subsequent movement of the 55 switch-points.

5. A switch-point lock comprising, in combination with the switch-points and an end- 60 wise movable rod attached to and extending laterally therefrom, a locking device coöperating with the outer end of said rod including a swinging operating lever and means whereby said lever is arrested in a lock-set 65 position to release the switch-points, con-

structed upon subsequent shifting of the switch-points and endwise movement of said rod to permit said lever to automatically swing into position to lock the switch-points in place.

70

6. A switch point lock consisting of a longitudinally reciprocating lock rod connected at its inner end with the switch-points, a locking device located at the side of the track and independent of the switch actuating mechanism, and interlocking parts on the outer end of said rod and the locking device which are brought into position for engagement and release by endwise movement of the lock-rod.

75

7. A switch point lock consisting of a lock 80 rod independent of the switch operating mechanism connected with the switch points and provided at its outer end with two locking devices separated from each other a distance substantially equal to the throw of the switch, and locking devices coöperating with the locking devices on the lock rod for positively locking the switch points in either of the positions thereof.

80

8. A switch point lock consisting of a lock- 90 ing device independent of the switch actuating mechanism, a lock rod connected at one end with the switch points and provided at its other end with notches separated longitudinally of the switch rod and detents carried 95 by the locking device for separately engaging said locking notches for the purpose set forth.

95

9. A switch point lock consisting of a locking device, a lock-rod connected at one end with the switch points and provided at its 100 other end with longitudinally separated notches, detents carried by the locking device for separately engaging said locking notches, and a lever for giving movement to said detents.

105

10. A switch point lock consisting of a locking device, a lock-rod connected at one end with the switch points and provided at its other end with longitudinally separated notches, detents carried by the locking device for separately engaging said locking notches, a lever for giving movement to said 110 detents, and means whereby the lever and said detents are arrested in a lock-set position and arranged to permit automatic locking 115 of said rod upon subsequent shifting of the switch points.

110

11. A switch point lock consisting of a locking device independent of the switch actuating mechanism, a lock rod connected at its 120 inner end with the switch points and provided at its outer end with notches separated longitudinally of the switch rod, said locking device embracing a sliding locking frame through which said rod extends, and 125 detents carried by said sliding frame adapted for separate engagement with said notches.

120

12. A switch point lock consisting of a locking device, and an endwise movable lock-rod connected at its inner end with the switch- 130

points and provided at its outer end with notches separated longitudinally of the switch-rod, said locking device embracing a sliding member, and detents carried by said 5 sliding member adapted for separate engagement with said notches.

13. A switch point lock consisting of a locking device located at the side of the track and independent of the switch actuating mechanism, and a lock rod connected at its inner end with the switch points, and provided at its outer end with upwardly and downwardly opening notches separated longitudinally of the rod, said locking device embracing a sliding locking frame movable transversely of the lock rod and through which the rod extends, and upper and lower detents carried by the frame adapted severally for engagement with the upper and lower notches of the 20 rod.

14. A switch point lock consisting of a locking device independent of the switch actuating mechanism, and a lock rod connected at one end with the switch points and provided 25 at its other end with notches separated longitudinally of the rod, said locking device consisting of a base disposed transversely of the rod and apertured for guiding engagement with the outer end of the lock rod, a locking 30 frame sliding endwise of the base through which also the rod extends, and detents carried by said frame adapted for separate engagement with said notches.

15. A switch point lock consisting of a locking device, and an endwise movable lock-rod connected at its inner end with the switch-points and provided at its outer end with notches separated longitudinally of the switch-rod, said locking device embracing a 35 sliding member, detents carried by said sliding member adapted for separate engagement with said notches, and rack and gear mechanism for sliding said member.

16. A switch point lock consisting of a locking device, and an endwise movable lock-rod connected at its inner end with the switch-points and provided at its outer end with notches separated longitudinally of the switch-rod, said locking device embracing a 45 sliding member, detents carried by said sliding member adapted for separate engagement with said notches, and rack and gear mechanism for sliding said member.

50

with said notches, and a swinging lever for giving endwise movement to said sliding member.

17. A switch point lock consisting of a locking device independent of the switch actuating mechanism, and a lock rod connected at one end with the switch points and provided at its other end with notches separated longitudinally of the rod, said locking device 60 consisting of a base disposed transversely of the rod and apertured for guiding engagement with the outer end of the lock rod, a locking frame sliding endwise of the base through which also the rod extends, detents 65 carried by said frame adapted for separate engagement with said notches, and rack and gear mechanism for sliding said frame.

18. A switch point lock consisting of a locking device independent of the switch actuating mechanism, and a lock rod connected at one end with the switch points and provided at its other end with notches separated longitudinally of the rod, said locking device consisting of a base disposed transversely of 75 the rod and apertured for guiding engagement with the outer end of the lock rod, a locking frame sliding endwise of the base through which also the rod extends, detents carried by said frame adapted for engagement with said notches, and means for giving endwise movement to said frame comprising a rack on the frame, a gear segment engaging the rack and a weight lever for rotating said gear.

19. In a switch-point lock the combination with the endwise movable lock-rod, a detent adapted to engage a notch or shoulder on the lock-rod to lock the same from endwise movement, a lever for operating said detent, 90 means whereby the lever may be set in a lock-set position and means whereby the lever falls to its locking position upon endwise movement of the lock-rod.

In testimony, that I claim the foregoing as 95 my invention I affix my signature in the presence of two witnesses, this 25th day of September A. D. 1906.

JAMES B. LATIMER.
